GRAVE MARKER

George N. White, 3586 Hartford Ave.,
Butte, Mont. 59701

Filed Apr. 13, 1973, Ser. No. 350,769

Term of patent 14 years

Int. Cl. D20—03

U.S. Cl. D31—14

FIG. 1

FIG. 2

FIG. 3

FIG. 1 is a view in perspective as seen from the top, front and one side of a grave marker, showing my new design;

FIG. 2 is a view in perspective as seen from the bottom, front, and one side; and

FIG. 3 is a view in side elevation as seen from the side opposite that shown in FIG. 1.

The rear thereof, not shown, is plain and devoid of ornamentation.

I claim:

The ornamental design for a grave marker, substantially as shown and described.
